(57) **CLAIM**

The ornamental design for a medical injector with enhanced grip, as shown and described.

DESCRIPTION

FIG. 1 is a perspective view of a medical injector with an enhanced grip showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is an enlarged top plan view thereof; and, FIG. 7 is an enlarged bottom plan view thereof.

Portions of the medical injector with enhanced grip shown in dashed lines in FIGS. 4, 5, and 7 depict unclaimed portions of the medical injector with enhanced grip that are included for environmental purposes only.

1 Claim, 5 Drawing Sheets
